[57] CLAIM

The ornamental design for a combined template and frame, substantially as shown and described.

DESCRIPTION

FIG. 1 is a top plan view of a combined template and frame, showing my new design, the bottom surface being plain and unornamented;

FIG. 2 is a top perspective view thereof;

FIG. 3 is a side elevational view thereof;

FIG. 4 is an end elevational view thereof;
FIG. 5 is a cross-sectional view thereof taken along line 5—5 of FIG. 1.
